UNITED STATES PATENT OFFICE.

GEORGE T. LADD, OF PITTSBURGH, PENNSYLVANIA.

WATER-TUBE BOILER.

1,130,746.

Specification of Letters Patent.

Patented Mar. 9, 1915.

Application filed September 21, 1914. Serial No. 862,710.

To all whom it may concern:

Be it known that I, George T. Ladd, residing at Pittsburgh, in the county of Allegheny and State of Pennsylvania, a citizen of the United States, have invented or discovered certain new and useful Improvements in Water-Tube Boilers, of which improvements the following is a specification.

The invention described herein relates to certain improvements in feed boxes for boilers. These feed boxes are so arranged that the feed water will flow therefrom into the circulating system of the boiler, the lower ends of tubes forming a part of such system being inclosed by the box. In flowing up through these tubes the water is raised to a temperature at which the insoluble constituents are precipitated and will settle down into the box.

The invention has for its object a construction permitting of the blowing off from time to time of the greater part of such precipitates, and the easy access to the interior of the box for the removal of solid matter which may cake on the inner surfaces of the box and cannot be blown out.

The invention is hereinafter more fully described and claimed.

In the accompanying drawings forming a part of this specification, Figure 1 is a sectional view on a vertical plane of a portion of the lower drum of a vertical water tube boiler, having my improved feed box arranged therein, and Fig. 2 is a longitudinal section of the drum to one side of the box.

The drum 1 is of any suitable form or construction and is provided as usual with a man hole and cover 2 in its end. Within this drum is arranged a feed box which in 40 closes the inner end of the feed water supply pipe 3, and also the lower ends of some of the tubes 4 connecting the lower with the upper drum (not shown). This box consists of end walls 5 having their upper edges 45 flanged inwardly as at 6, a main side or outer wall 7, bolted or otherwise secured to the flanges 6, and a detachable hood cap 8.

In order that the box may be made of suitable width, it is preferred to make the 50 top wall in two longitudinal sections to permit of their insertion through the man hole in the end of the drum. This box is held in position in the drum by means of hinges 9 having their members secured respectively 55 to the drum and to the side of the box along one side thereof. Any suitable means may

be employed for holding the box in closed or operative position, such for example as that shown, consisting of a pivotally mounted pin 10, having a reduced stem or end 11 adapted to extend through the top of the box and slotted for the reception of a wedge 12.

By reference to Fig. 1 it will be seen that the box, if the side were made of a width equal to the length of the end pieces, could not be turned back to permit of access to the inner ends of the tubes 4, while a man is within the drum. In order to permit of this shifting of the box, the side wall 7 does not extend the full width of the box, and that a complete closure of the box is effected by a removable hood or cap 8. The ends of this hood rest on the end walls 5, one edge bears against the inner wall of the drum, between the ends of adjacent rows of tubes, and the opposite edge rests on a ledge formed by a strip of metal 11 riveted to the side wall 7. The hood is held in position by means of buttons 14 mounted on the ends 11 of the pins 10. In addition to permitting of the turning back of the box as before stated the removable hood admits of easy access to the interior of the box for the removal of material which cannot be blown out as hereinafter described.

The blow-off pipe or pipes 15 extend through the wall of the drum into the box on the side opposite the inner ends of the tubes 4 as shown in Fig. 1, so that when the blow-off valve is opened the water will rush across the box sweeping the sludge toward and through the blow-off pipe. As the streams of water will converge toward the blow-off pipe, deposits at the ends and other parts of the box may not be entirely removed. Provision is therefore made for causing the water to flow adjacent to the ends and all other parts of the box toward the outlet or blow-off pipe. To this end a wall or partition 16 is so arranged longitudinally of the box and preferably secured to its side wall as shown, so as to form a blow-off chamber with which the blow-off pipe connects. A series of holes 17 are formed at suitable intervals through this partition having a combined capacity suitably proportioned relative to the delivery capacity of the blow-off pipe, so that there will be a strong flow of water through all the holes and from each 110 of the latter toward the blow-off pipe. As the holes are distributed along the entire

length of the partition, all parts of the box will be brought under the action of the water flowing from the tubes 4.

I claim herein as my invention:

5. 1. The combination with a water tube boiler, of a box arranged in one of the drums to inclose and isolate the ends of a portion of the circulating tubes, and the blow-off nozzle, and a perforated partition interposed between the ends of the tubes and the blow-off nozzle.
- 10 2. The combination with a water tube boiler, of a box arranged in one of the drums to inclose and isolate the ends of a portion of the circulating tubes and the feed and blow-off nozzles, a portion of the side or outer wall of the box being detachable.
- 15 3. The combination with a water tube boiler, of a box hinged to the drum and adapted to inclose and isolate the ends of a portion of the circulating tubes and the feed and blow-off nozzles, a portion of the main or outer wall of the box being detachable.

4. The combination with a water tube boiler, of a box hinged to the drum and 25 adapted to inclose and isolate the ends of a portion of the circulating tubes and the feed and blow-off nozzles, a portion of the box being detachable, and means for holding the box and detachable portion in operative position.

5. The combination with a water tube boiler, of a box arranged in one of the drums to inclose and isolate the ends of a portion of the circulating tubes and the feed and 35 blow-off nozzles, said box being provided with a chamber surrounding the outlet of the blow-off nozzle and connected with the portion of the box inclosing the ends of the circulating tubes.

In testimony whereof, I have hereunto set my hand.

GEORGE T. LADD.
